UNITED STATES PATENT OFFICE.

JOHN M. EVANS, OF SAN FRANCISCO, CALIFORNIA, ASSIGNOR, BY MESNE ASSIGNMENTS, TO STANDARD OIL COMPANY OF CALIFORNIA, OF SAN FRANCISCO, CALIFORNIA, A CORPORATION OF DELAWARE.

VAPOR LINE FOR OIL TANKS.

Application filed November 20, 1924. Serial No. 751,103.

This invention relates to vapor lines for oil tanks and is more particularly directed to an apparatus for the reduction of evaporation losses from working tanks containing volatile fluids such as gasoline, crude petroleum, and the like.

In a tank for the storage of crude oil, gasoline or the like, the loss from vaporization is a serious factor in the storage of such liquids.

When a tank is being filled the air above the surface of the liquid becomes saturated with the light and most valuable contents of the oil and as the filling of the tank proceeds this air saturated with the light vapors must be forced outward through the top of the tank which results in a very considerable loss.

In emptying a tank, unless means are provided for allowing gas or air to enter the tank, a vacuum is created within the tank. If the hatch or manhole in the top of the tank is opened and air drawn into the tank, the air becomes saturated with the vapor and in filling the tank again, as above pointed out, the vapor contained in this air is completely lost. Such forcing of air saturated with volatile vapors outward from the top of the tank produces a great fire hazard.

This invention, therefore, relates to the operation of pairs of those tanks, usually termed "working" tanks, or there may be several tanks in the group, so that as one tank is being emptied and another tank is being filled the vapor expelled from the tank being filled is conveyed to the tank being emptied to supply a portion or all of the gas necessary to relieve the vacuum produced therein.

This invention consists primarily of a pipe line carrying the vapor in conjunction with which vacuum and pressure relief valves to regulate the pressure in the tanks and other apertures are embodied herein to reduce the hazard from fire and from unsafe pressure.

The object of this invention is to produce a new and improved system for conveying the vapor from a tank being filled to a tank being emptied for the preservation of the valuable constituents of that vapor.

An object of this invention is to provide a new and improved system of vapor or gas transportation between working tanks, in

which means are provided to closely regulate the pressure in the tanks.

Other objects and advantages of this invention will be apparent from the detailed description of a preferred embodiment thereof as illustrated in the accompanying drawings.

In the drawings:

Figure 1 is a side elevation of a vapor line between volatile liquid tanks, embodying this invention.

Fig. 2 is an enlarged side elevation partly in section of a pressure and vacuum relief means embodied in this invention.

In the drawings, 1 indicates a pipe line of suitable size conveying vapor between the tanks 2, 2 in which line 1 pressure and relief valves 3, 3 and 4 are adapted to control the pressure in the tanks 2, 2 and in line 1 and to allow the escape of excess vapors, which pressure and vacuum relief valves 3, 3 and 4 are the subject of the co-pending application of John Kuhl, filed November 25, 1924, Serial Number 752,276.

The said pressure and vacuum relief valves are mounted on each tank, as at 5 and at a centrally located point 6 in the line 1, or they may be placed only on one or more of the tanks 2, or only at the central point 6. However, it is preferred for safety to mount such a valve on each tank 2 and at the centrally located point 6. With this arrangement, it is preferable to have the relief valves 3, 3 set to open at pressure or vacuum of about one inch of water and the central valve 4 set to open at about one-half inch of water. With this differential and proper line sizes all, or most, of the excess vapor which must be forced from the system will be discharged at the central point 6, which being located well away from the tanks 2, minimizes fire hazard. It, however, being understood that if desired the excess vapors discharged at this point may be conveyed by another pipe to any suitable recovery system, such as a compressor plant or refrigeration plant, or otherwise disposed of. If the quantity of such vapor is too great for the central valve 4 to handle, or the said valve 4 becomes inoperative for any cause, the discharge will occur through the tank pressure relief valves 3. The same is true of the operation of the central and tank vacuum relief valves.

100
105

The pressure and vacuum relief valves 3, 3 and 4, comprise a body 16 having tapered openings 17, 17 and 18, 18 in the top and bottom thereof for holding the seats 19 of 5 vacuum and pressure relief valves 20 and making a gas-tight connection between the main body and valve seat. A cylindrical opening 21 is bored in the top of the body 16 near the center thereof and a similar 10 opening 22 is bored in the bottom of the body 16 to register with the bore 21. The said openings 21 and 22 are adapted to receive a cylindrical screen flash arrester 23 and for making a gas-tight connection between the body 16 and said flash arrester 23. Secured to the body 16 and spaced 15 therefrom is a hood 24. The construction and operation of this cylindrical screen fire arrester 23 is particularly pointed out in that 20 co-pending application of John Kuhl, here- tofore referred to. The pressure and vacuum relief valves 20 are of the liquid seal type and are particularly described in that co-pending application of John Kuhl, above 25 referred to, and comprises a seat 19 having a circular groove 25 adapted to be filled with mercury or similar fluid and have a cross or connecting web 26, having a central bore 27 through which a valve stem 28 is adapted 30 to pass. Secured to the upper end of the valve stem 28 is a valve head 29 adapted to seat within the mercury groove 25. Secured to a cylindrical boss 30 of the seat 19 by any suitable device, such as a cap screw 31, 35 is a dash pot 32. Means are provided for guiding the valve stem 28 within the dash pot 32 which means are generally indicated at 33. A pin 34 passes through the valve stem 28 and is adapted to engage the inner 40 side of the bore 27 so as to limit the opening of the valve 20.

In combination with the vapor line 1 the 45 valves 3, 3 and 4, and as an integral part of the system, are flame arresters 7 which are the subject of that co-pending application of Hubert H. Hall, filed November 28, 1924, Serial Number 754,452, (Patent No. 1,586,195, granted May 25, 1926) which are 50 designed to prevent a flame or explosive force from traveling through the pipe line

1. They may be located at a convenient point or points in the line 1, such as just inside the firebank 8 surrounding each tank 2. The flame arresters 7 also serve in this system as emergency pressure and vacuum 65 reliefs so that when the valves 3, 3 and 4 become inoperative from any cause, the tanks 2 will not be in danger by excessive pressure or vacuum.

Gate valves 9 may be located in the line 60 1 so that any tank 2 can be isolated from the system when necessary. At the low points in the system where liquid condensate may form and collect, drainage lines 10 are provided to allow automatic and continuous 65 drainage of the condensate without loss of the vapor formed or the admission of air into the system. Small pipe lines 11 of about one inch size may be installed connected to each tank roof as at 12 and meeting at some 70 convenient point 13 connect with instruments 14 which indicate or record the pressure or vacuum existing in the tanks 2 and if desired at other points in the system. Also at this junction electric connections may 75 be provided to operate a bell or horn 15 or other alarm device whenever excessive pressure or vacuum exists in the tanks.

Having fully described a preferred embodiment of the invention, it is to be understood that it is not intended to limit the invention to the exact construction and details herein set forth which may obviously be varied within the spirit of the appended claim.

I claim:

In a vapor recovery system, a pair of spaced working tanks, a pipe line adapted 80 to convey vapor between the working tanks, pressure relief means within the line and pressure relief means connected with the 90 roof of each of said working tanks, means disposed within the pipe line and spaced from the said tanks for arresting fire, and means connected to a low point of the said pipe line for the drainage of condensate 95 therefrom.

Signed at San Francisco, California, this 3rd day of November, 1924.

JOHN M. EVANS.
